(57) **CLAIM**

The ornamental design for a telephone receiver mask, as shown and described.

DESCRIPTION

FIG. 1 is a Front Perspective View of the telephone receiver mask invention;

FIG. 2 is a Front View of the telephone receiver mask invention;

FIG. 3 is a Back View of the telephone receiver mask invention;

FIG. 4 is a Left Side View of the telephone receiver mask invention;

FIG. 5 is a Right Side View of the telephone receiver mask invention;

FIG. 6 is a Top View of the telephone receiver mask invention;

FIG. 7 is a Bottom View of the Telephone Receiver Mask invention;

FIG. 8 is an In Use Perspective View of the telephone receiver mask invention; said invention shown as installed on a first telephone receiver;

FIG. 9 is an In Use Perspective View of the telephone receiver mask invention, said invention shown as installed on a second telephone receiver;

FIG. 10 is an In Use Perspective View of the telephone receiver mask invention; said invention shown as installed on a third telephone receiver; and,

(Continued)

FIG. 11 is an In Use perspective view of the telephone receiver mask invention; said invention shown as installed on a fourth telephone receiver.

The broken lines illustrating a telephone receiver in FIGS. 8-11 depict environment and form no part of the claimed design.

1 Claim, 9 Drawing Sheets
